UNITED STATES PATENT OFFICE.

WILLIAM DOWNING WILKINSON, OF TORONTO, CANADA.

DESIGN FOR A FRAME FOR SASH-FASTENERS.

SPECIFICATION forming part of Design No. 23,939, dated January 1, 1895.

Application filed June 25, 1894. Serial No. 515,698. Term of patent 7 years.

To all whom it may concern:

Be it known that I, WILLIAM DOWNING WILKINSON, of Toronto, in the Province of Ontario and Dominion of Canada, have invented and produced a new and original Design for a Sash-Fastener Frame, of which the following is a full, clear, and exact specification.

Reference is to be had to the accompanying drawings, forming a part of this specification, in which similar letters of reference indicate corresponding parts in both the figures.

Figure 1 represents a front perspective view of a sash fastener frame embodying my new design; and Fig. 2 is a rear perspective view of the same.

The leading feature of my design consists in the novel configuration shown, which is as follows: The base *a* is flat as shown and from

said base there rise vertically the plane sides *b*, which present separate spaced figures at the front and top, the lines thereof merging at the back, a short distance above the flat surface of the base, into a single figure *c*. Further, the lines of the sides *b* at their upper edges range obliquely as at *d*, from the back figure *c* toward the front, and said oblique lines and the vertical front lines merge into the rounded top edge lines *e*. The oblique edge lines of the sides *b* are crossed near the top by a transverse angular figure *g*.

I claim—

The design for a sash fastener frame herein shown and described.

WILLIAM DOWNING WILKINSON.
